INKSTAND

Herman Frederick Krueger, Los Angeles, Calif.

Application March 16, 1938, Serial No. 196,111

2 Claims. (Cl. 120—59)

My invention relates to improvements in ink-stands in which ink is automatically supplied from a storage container to a reservoir.

Among the objects of my invention, I aim to provide an easily refillable ink container from which ink flows by gravity to the reservoir as ink is consumed therefrom, and in which the reservoir ink level is controlled by hydrostatic pressure. Heretofore it has been difficult to refill such devices, particularly while some ink is still present in the container, for the reason that when atmospheric pressure is communicated to the liquid surface in the container it causes the reservoir to overflow. It is a further object of my invention to provide means for automatically sealing the outlet of the container into the reservoir before the container is opened to atmosphere.

Generally stated, I accomplish these ends by providing, in association with a reservoir, a relatively large ink container having a refilling opening at its top and an outlet at its bottom, which outlet is normally submerged in the ink in the reservoir. A spring actuated valve controls the outlet, said valve having a stem which is normally pushed downwardly by the cover cap of the refilling opening, to maintain the valve in open position until the cover cap is removed or sufficiently raised.

30 By way of example, in the annexed drawing, I illustrate in Fig. 1 a vertical sectional view of my device, with a pen shown in elevation; in Fig. 2 I show a variational form of device; and Fig. 3 is a section on line 3—3 of Fig. 2.

In the drawing, referring to Fig. 1, I show a
35 base 5 which may be formed of glass, Bakelite
or other suitable material and which may be of
any desired shape, although I prefer to make it
rectangular in horizontal section. The base has
an inner wall 6 providing an ink reservoir 7, the
40 inner wall presenting a circular, threaded top por-
tion 8. The front top wall of the base has a down-
wardly tapered portion 9 through which a cir-
cular opening 10 is provided to take a pen hold-
ing tube 11. Tube 11 has a flared mouth 11a
45 to facilitate insertion of the pen holder 12. An
air passing opening 15 through tube 11 and the
wall of the reservoir is provided over the ink level
L in the reservoir.

An ink container 20, shown as round in cross-section and which likewise may be formed of glass, Bakelite or other suitable material, has annular threads 21 by which the container is threadedly mounted in the top portion 8 of the base, and the bottom wall 22 tapers to the restricted outlet 23. The top wall 24 of the container has

a round flange 25 threaded at 26, said flange having a portion 27 of reduced diameter to take a soft rubber, cork or other suitable washer 28, the washer resting against annular shoulder 29 on the flange. A cover cap 30 is threaded onto the flanged neck 25, said cap presenting a central downwardly opening socket member 31 for the purposes now to be described. 5

For automatically closing orifice 23 when cover cap 30 is removed or sufficiently unscrewed from the neck, I show a conical valve 35 adapted to seat against orifice wall 23. The bottom portion of valve 35 has a central recess 36 in which seats one end of a coil spring 37, the other end of the spring fitting over a lug 38 depending upwardly from the bottom wall of the reservoir. To prevent rocking movement of the coil spring 37 I preferably make it frusto-conical in shape as shown. Valve 35 has an upwardly extending stem 40, which may be formed integral with or suitably affixed to the valve member and which fits at its top end in socket 34. The length of stem 40 is such that when cover cap 30 is fully screwed down on neck 25 the valve 35 is pushed downward, against spring 37, from contact with orifice 23 to permit ink to pass from the container into the reservoir.

When it is desired to refill the container, cap 30 is unscrewed, which permits the spring 37 to move the valve 35 against orifice 23 to close it before atmospheric pressure is communicated to the inside of the container through the neck over liquid level L'. To insure that the seal provided by the cap will not be broken until valve 25 is closed, a soft rubber or other suitably yieldable washer 28 is provided around the neck adjacent its top portion. When the cap is fully screwed down on the neck, this washer is compressed between the top wall of the cap and shoulder 29 of the neck, and the width of the washer is such that as it resumes its normal width as the compression is relieved, the washer will extend slightly above the top of the neck so as to maintain a seal as the cap is being removed.

In the device of Figs. 2 and 3, there is a base 45 having an inner wall 6a, a reservoir 7a, a pen holder 11b, an opening 15b and a threaded top portion 8a of the construction hereinabove described. Also the container 28a has a discharge orifice 23a, a neck 25a, a cap 30a and a washer 28a of the construction hereinabove described except that, in lieu of the downwardly depending socket member 31 of Fig. 1, the socket for valve stem 40a is shown as a conical recess 50 formed centrally of the inside wall of the cap, and the 55

- neck has an inner annular flange 51 at its bottom. Here valve 35a is moved into contact with orifice 23a to close the outlet by means of stem 40a passing through the upwardly bowed leaf 5. The spring rests at its ends on flange 51 and stem 40a is crimped at 56 immediately over its point of emergence from the opening 55a through the spring so that as the spring bows upwardly when the cap is removed, the valve stem 10 is moved upwardly to close the outlet orifice.
- The details illustrated in the drawing and described hereinabove are for the purpose of making my invention clear and it will be obvious that various modifications may be made without departing from the scope of the invention as defined by the following claims.

I claim:

1. An inkstand comprising a base forming an ink chamber, an ink container mounted on the base, said container having an inlet through which the container may be filled and an outlet communicating with the chamber, a valve controlling the outlet, means for moving the valve into outlet closing position, a removable cap normally closing the inlet, a valve stem extending from the valve into the inlet in position to have one of its ends engaged by the cap to move the valve into outlet opening position, and a resilient sealing member surrounding the inlet and being expandable against the cap to prevent admission of air

through the inlet, while the cap is being removed therefrom, until the cap is sufficiently moved to permit the outlet valve to move into closing position.

2. In an inkstand comprising a base forming an ink chamber, an ink container mounted on the base, said container having a neck portion provided with an inlet opening and having an outlet communicating with the ink chamber, the lower portion of said neck being threaded and the upper portion being of reduced diameter to present a shoulder between the upper and lower portion of the neck, a valve controlling the outlet, resilient means urging the valve into outlet closing position, a cap screwthreaded onto the inlet neck for normally closing the inlet, a valve stem connected at its lower end to the valve and extending upwardly into the neck in position to be engaged by and pressed downwardly into valve opening position when the cap is screwed onto the neck, and a resilient sealing washer mounted on the reduced portion of the neck and being compressible against the shoulder by the cap when the cap is screwed onto the neck, said washer being of a thickness and resiliency sufficient to expand and form an air tight contact with the neck and cap, during unscrewing of the cap from the neck, until the valve is moved into outlet closing position.

HERMAN FREDERICK KRUEGER. 30
